UNITED STATES PATENT OFFICE

ERNEST BLAKELOCK THUBRON, OF NAPIER, NEW ZEALAND

BOTTLING OF LIQUIDS

Application filed October 22, 1926, Serial No. 143,438, and in New Zealand November 12, 1925.

This invention relates to the bottling of liquids, and provides an improved method of, and apparatus for the aforesaid purpose.

At the present time in the bottling of liquids it is necessary to leave the bottles either open to the atmosphere, or to open the same to the atmosphere at intervals, to allow the air displaced by the liquid to escape, the bottles and their contents being further opened to the atmosphere prior to the sealing of the bottles which is a step performed independently of the filling operation.

Disadvantages arising from the above mentioned operations are that the filling of the bottles is retarded by the air therein, and the opening of the bottles to the atmosphere renders the bottles and the contents thereof, such as milk, liable to contamination, and when dealing with liquids under pressure, results in the loss of pressure, and the loss of gas used in the manufacture of aerated beverages, and further it is necessary to employ separate means for sealing the bottles.

The present invention has the object of overcoming the disadvantages above enumerated, and in general a view of providing a method of, and apparatus, which will enable liquids to be bottled more economically and under better hygienic conditions than those attendant upon present day bottling methods and apparatus.

An essential feature of the invention, is the removal of air from the bottles before charging the latter with liquid, so that the latter will readily pass to the bottles without interruption, whether under pressure or simply by gravity, while a further and important feature of the invention, is that the bottles and their contents are not opened to the atmosphere, until such time as the bottles are opened for use, sealing of the latter being effected in the same apparatus as that from which the bottles are evacuated of air and charged with liquid.

The improved method, consists in first evacuating a bottle of air, placing liquid in the bottle, and sealing the latter without opening the same or its contents to the atmosphere.

If necessary liquid to be placed in the bottle

can have air removed therefrom either after being placed in the bottle or while in a reservoir from which the bottles receive the liquid.

When dealing with nonaerated beverages, the liquid simply flows by gravity from the reservoir to the bottles, and when dealing with aerated beverages, the liquid passes under pressure generated by the gas mixed with the liquid, to the bottles.

Apparatus for enabling the evacuating, filling and sealing of the bottles to be carried out as before described, comprises a machine having mounted thereon a bottling head in communication with a source of vacuum and also adapted to be opened when required to a reservoir containing liquid to be bottled.

A support for the bottles, presses the mouths of the latter up into the head, wherein is provided a ring or cushion of soft material for contacting with the bottle and sealing the entrance to the head, while operable vertically in the latter, is a piston adapted to contact with the bottle closure, and capable of being used to force sealed bottles from the head.

The piston can also be used for the purpose of lifting the closure to be used in or on the bottle, clear of the mouth thereof while the bottle is evacuated of air and charged with liquid after which the closure is applied to the bottle, and the latter ejected from the head by the piston.

The invention will however, be more particularly described with the aid of the accompanying drawings, wherein:—

Figure 1 is a side elevation of the machine, and

Figure 2 a part elevation of the opposite side of the same,

Figure 3 is a vertical section of the bottling head as used in Figures 1 and 2, and adapted for applying crown corks to bottles.

Figure 4 is a part vertical section of the bottling head showing the means for retaining the crown corks in their raised positions during evacuation and filling of bottles.

Figure 5 is a sectional plan view taken on the line A—A, Figure 3, but showing alternative means for retaining the crown corks in their raised positions,

Figure 6 is a part elevation and part sectional elevation showing the construction and mounting of the bottle supporting table.

Figure 7 is a detail in elevation of the foot actuated means for operating the table.

Figure 8 is a detail in elevation, of the control lever and means for operating the water control to the ejector, and the vacuum control to the bottling head.

10 Figure 9 is a detail in elevation showing the means for controlling the supply of liquid to the bottling head.

15 Figure 10 is a vertical section of the lower portion of a bottling head for use in bottling milk, and

Figure 11 is a vertical section of the upper portion of said head, while

Figure 12 is a sectional plan view taken on the line B—B Figure 10, and

20 Figure 13 is a sectional elevation of a water operated ejector for exhausting air from the bottling head.

The machine comprises a base 1 from which rises a hollow column 2, on which is supported a liquid reservoir 3, a bottling head 4, a bottle guide 5, a bottle supporting table 6, and an ejector or air exhauster 7.

To the base 1 is pivoted at 8a a foot lever 8, the latter being connected by a link 9 with 30 one end of a tension spring 10 located in the column 2, and having its other end connected by a rod or the like 11, provided with one or more adjusting nuts 12, with the upper end of said column 2.

35 The foot lever 8 is slotted and pivotally connected to the lower end of a vertical rod 13, the upper end of which is entered in the hollow stem of the bottle supporting table 6, (Figure 6) the latter having a pad of rubber 100 or the like 14, recessed therein and being operable vertically in a bracket 15 clamped or secured to the hollow column 2 at the desired height thereon.

40 The rod 13 is preferably in two portions, 45 united by a coupling 16 (Figure 1) screw threaded with right and left handed threads to enable the length of the rod to be adjusted as required. Also said foot lever 8 has pivoted at its outer end a pedal 17 (Figures 1 and 7) provided with a catch 18 adapted to be engaged in notches 19 in a quadrant 20 secured to the base 1, or other convenient part of the machine, said pedal 17 being provided with a kick out trigger 21 for disengaging the catch 18 from any notch 19 of the quadrant 20 in which it may be engaged.

45 Mounted on the bracket 15 in which the aforesaid table 6, works, is a cross shaft 22 (Figures 1 and 6) having keyed thereon, a hand lever 23, and a pair of arms 24, the latter passing one at each side of the table bracket 15, and having their outer ends slotted to receive the ends of a cross pin 25 entered in a slot 26, in the vertical rod 13 aforesaid, said pin 25 being secured to the

stem of the table 6, and operating vertically in slots 27 provided in the portion of the bracket 15 in which the table stem rises and falls.

Also mounted on the table bracket 15, 70 clamped on the hollow column 2, is a further cross shaft 28 (Figures 2 and 6) the latter having secured thereon a further hand lever 29 and an arm 30 provided with a tooth 30a adapted to engage over the upper edge of the 75 table 6, and in a recess or notch 31 (Figure 6) therein. This last mentioned arm 30 is provided with a spring 32 for causing its tooth 30a to engage the table 6 and also with a stop 33 for limiting the movement of the 80 arm away from the table 6, and the spring 32 is designed to be compressed between the arm 30 and column 2 and the stop 33 to strike the latter.

85 The bottle guide 5 is attached to a bracket 34 which is adjustably clamped to the hollow column 2 and said guide is provided for ensuring the correct positioning of the bottle 35 in relation to the bottling head of the machine.

90 The table 6 can be raised and lowered to bring a bottle 35 placed thereon, to the positions required in evacuating, filling and crowning or sealing, by operating either the foot lever 8 or the hand lever 23 on the shaft 95 22 having the arms 24 pivoted to the cross pin 25 secured through the table stem, and the required positions can be obtained either by engaging the catch 18 on the pedal 17 in the notched quadrant 20 as is necessary, or 100 by causing the toothed arm 30 aforesaid to engage the table 6 as before mentioned. Crowning or sealing of the bottle 35 can be effected either by the contraction of the tension spring 10 in the hollow column 2, which 105 is utilized to force the table 6 and bottle 35 upwards, or by operating the hand lever 23 to obtain the necessary upward movement 110 of the table 6 and bottle thereon.

The bottling head 4, the ejector 7, and the reservoir 3, for the liquid to be bottled are mounted on brackets 36 clamped to the hollow column 2, and a valve 37, for controlling the passage of water to the ejector 7, and a valve 38 for controlling the action of vacuum 115 created by the latter in the bottling head 4, are both controlled by a single hand lever 39 keyed on a shaft 40 mounted on one of the supporting brackets 36.

120 This shaft 40 (Figures 1, 2 and 8) has keyed on one end a boss 41 having approximately opposed forked extensions 41a one of which passes upon the stem of the water control valve 37, while the other of said extensions 41a passes upon the stem of the vacuum control valve 38, both valves being spring loaded to normally close while their stems are provided with nuts 42 against which the forked extensions 41a work.

125 The forked extensions 41a and the nuts 130

42 are arranged so that when the hand lever 39 is operated to open said valves 37, 38 the water control valve 37 opens in advance of the vacuum control valve 38 and when said lever 39 is operated to permit the valves to close, the vacuum control valve 38 closes before the water control valve 37.

The valve operating hand lever 39 is forked, and has mounted loosely on its shaft 40, and in its fork, an arm 43 (Figures 2 and 9) for opening and closing a valve 44 controlling the passage of liquid from the liquid reservoir 3 to the bottling head 4.

This loosely mounted arm 43 is also forked to pass upon and engage the stem of the valve 44 in a manner similar to which the forked extensions 41a aforesaid pass upon and engage the stems of the water, and vacuum control valves 37, 38. Said loosely mounted arm 43 is provided with a notch 43a, adapted to be engaged by a tooth 45a on a catch lever 45 pivoted on the valve operating hand lever 39, when the latter is continued to be moved in the direction in which it is moved to effect the closing of the water and vacuum control valves 37, 38 but after the latter have been closed. The catch lever 45 is operated to cause it to be engaged with, and be disengaged from the notch 43a in the loosely mounted arm 43 by a rod 46, passing through the lever handle and adapted to be actuated against the action of a spring 47 housed therein.

Upon the loosely mounted arm 43 and the catch lever 45 on the hand lever 39 being interengaged the latter can be returned forward to cause the said arm 43 to open the valve 44 on the pipe 48 (Figure 2) between the liquid reservoir 3 and the bottling head 4 without opening the valve 37 controlling the passage of water to the ejector 7, and the valve 38 controlling the action of vacuum in the bottling head 4.

The pipe 49 (Figures 1 and 2) through which vacuum acts, from the ejector 7 to the bottling head 4 is fitted with a nonreturn or check valve 50, and with a trap 51 containing a baffle plate for preventing the passage of moisture to the bottling head 4.

A connection 52 fitted with a stop cock can be provided between the pipe 49 and a pipe 53 rising in the reservoir 3, at one side thereof, to near the top for the purpose of enabling vacuum created by water passing through the ejector 7, to act in said reservoir 3 and exhaust the latter, and if necessary its contents of air. Also said reservoir 3 is provided with stirrers 54 on a shaft 55 operable by an external hand wheel 56, for enabling the contents of said reservoir to be thoroughly mixed. The reservoir 3 is also fitted with a pressure gauge 57.

The bottling head 4 (Figure 3) comprises a hollow fitting having screwing on to its upper end, a cap 58 fitted with a stuffing box 59,

and having a retaining ring 60 screwing onto its lower end. Near its lower end said fitting is provided with an internal ring 61, below which is fitted an upwardly tapered throat piece 62, and below the latter, a metal ring 63, grooved or recessed as at 63a in its periphery, downwardly and inwardly inclined passages 67 formed through said ring 63 connecting the groove or recess 63a with the interior of the head. Inlet nipples 64 and 65, communicate with the groove or recess 63a one of said nipples being connected with the valve 44 and pipe 48 through which liquid is passed from the reservoir 3 to the bottling head 4, while the other of said nipples is connected with the valve 38 and pipe 49 through which vacuum created in the ejector acts. Below the ring 63 the internal diameter of the head 4 is increased to provide a shoulder, and between the latter and the retaining ring 60, an annular or hollow ring 66 is fitted.

The annular or hollow rubber ring 66 is adapted to receive water or other liquid under pressure in order that it may be distended inwardly to grip or contact all round the neck of a bottle inserted in the head 4 for the purpose of making an air tight joint and so prevent the admission of air to the head when it is desired to put the bottle under vacuum. This ring 66 is made channel shaped in cross section, its outer wall being provided by a metal ring 68 adapted to be gripped between the upper and lower portions of said rubber ring, when the retaining ring 60, which screws on the head 4, is screwed up, said metal ring 68, being provided with a nipple 69 screwing into a boss 69a and adapted to be connected through a three way cock (not shown) with a suitable source of supply, of liquid under pressure.

Crown corks for closing and sealing the bottles are delivered by gravity down a chute 70 detachably secured to the undersurface of the retaining ring 60, said chute containing an opening 71 located directly below the mouth of the head, and over which the corks come to rest, one at a time.

Means for retaining the crown corks in a raised position in the head 4 during the time the bottle is being evacuated of air and filled with liquid, or with liquid and gas, comprise spring pressed and approximately L shaped members 72 (Figure 4) housed in vertical slots 73 in the outer surface of the internally tapered throat piece 62 and hung from the upper edge of the latter by projections 72a, the lower portions 72b of said L shaped members passing through slots 74 in the upper portion of the ring 63 to which the inlet nipples 64 and 65 are connected, and projecting slightly into the interior of the head, the inner ends of the portions 72b of said L shaped members 72 being shaped to receive and hold the crown corks or the like at the

lower entrance to the tapered throat piece 62 and above the downwardly inclined passages 67 through the ring 63.

Operating vertically in the tapered throat piece 62 and annular or hollow rubber 66 is a piston 75 shaped to fit the crown corks and secured on a rod 76 passing upwards into a sleeve 77 which enters the top of the throat piece 62 and is provided at its lower end with an external ring 78 the latter resting under the influence of a spring 79, in compression on the inner ring 61 around the lower portion of the head 4, said spring 79 surrounding the sleeve 77 and being compressed between the ring 78 on the later, and the cap 58.

The piston rod 76 has secured thereto, cross pins 82 which work in vertical slots 80 in the sleeve 77, the slots 80 in the sleeve 77 permitting air to be exhausted from the interior 20 of the head through the central vertical passage 76a in the rod 76 and piston 75, when a vacuum connection is made at 82 between the upper portion of the head 4 and the air exhauster or ejector 7.

25 The evacuation through 82 is for the purpose of evacuating the head, and is only necessary for equalizing the pressure above and below the cap thereby preventing strain upon the cap due to the air pressure and also preventing possible premature closing of the cap upon the bottle. The port 76a is closed by the cap and the evacuation of the bottle itself is made through the port 65.

A vertical rod 83 entered in the sleeve 77 35 above the piston rod 76 between which the said vertical rod a coiled spring 84 is placed, passes through the stuffing box 59 on the cap 58, and is pivotally connected to a slotted hand lever 85, (Figures 1 and 2) pivoted to a bracket 86 on the hollow column 2, said hand lever 85 passing through the latter and a link or loop 11a in the rod 11 attached to the tension spring 10 in said column 2.

45 The piston rod 76 normally hangs by means of the pins 82 in the bottom of the slots 80 in the sleeve 77 so that the lower edge of the piston 75 is level with the opening in or entrance to the retaining ring 60, and with a crown cork in position over the opening 71 50 in the chute 70, the operations in evacuating a botte of air, filling same with liquid and securing the crown cork on the bottle are as follows.

The table 6 is adjusted so that when the bottle 35 is stood thereon, its mouth is a short distance below the opening 71, in the crown cork chute 70. This adjustment can be obtained either by depressing the foot lever 8 and engaging the catch 18 in a suitable notch 60 in the quadrant 20 or by depressing the table by means of the hand lever 23 and allowing the tooth 30a of the arm 30 to engage over the upper edge of said table. The table 6 with the bottle thereon is then caused to ascend by first disengaging the catch 30a

from over its edge by means of the hand lever 29, and either operating the handle lever 23 to force the bottle upwards, or by disengaging the catch 18 from the quadrant 20, to allow the spring 10 to draw the foot lever 8 and rod 13 upwards. Upward movement of the bottle causes the mouth thereof to enter the opening 71 in the crown cork chute 70 and to contact with the crown cork over said opening 71, the crown cork being forced upwards against the piston 75. Continued upward movement of the bottle raises the piston 75, the cross pins 82 in the rod 76 of which ascend in the slots 80 in the sleeve 77. The bottle is forced for enough upwards to cause the crown cork to enter the tapered throat piece 62 and to engage the inwardly sprung pressed L shaped members 72, which are located above the downwardly and inwardly inclined passages 67 through the ring 63.

The table 6 is then lowered to bring the bottle mouth just below the lower ends of the passages 67, leaving the crown cork retained in the throat piece by the L-shaped members 72, the lowering of the table being effected either per medium of the hand lever 23 or the foot lever 8.

The desired position of the table 6 to bring the bottle mouth to just below the lower ends of the passages 67 or as shown dotted in Figure 3, is obtained by either allowing the tooth 30a on the arm 30 to engage in the notch 31 on the table 6, or by engaging the catch 18 in a selected notch 19 in the quadrant 20.

With the bottle in this position, liquid 100 under pressure is allowed to enter the annular or hollow rubber ring 66 and the latter caused to grip the bottle neck or mouth, all round, and effectively seal the entrance to the head against the admission of air. If desired the table 6 can be further lowered and the bottle left hanging from the head. The control lever 39 is then moved to open the valves 37 and 38, and the vacuum created, exhausts the air from the bottle, through the head and upon the desired degree of vacuum being obtained said valves 37 and 38 are again closed, after which the control lever 39 is further operated to open the valve 44, and permit liquid to pass from the reservoir 3 110 through the head into the bottle, and upon the latter being filled to the desired level, the supply of liquid is cut off. If the reservoir 3 does not happen to be under vacuum, air 115 can be exhausted from the bottle after filling so as to remove the air from the contents of the latter.

By then forcing the bottle upwards, either by a quick movement of the hand lever 23, or by kicking the trigger 21 to release the foot lever 8 and permit the latter to move suddenly upwards under the action of the spring 10, the bottle mouth and the crown cork above same are forced upwards into the tapered throat piece 62, which latter causes the 130

crown cork to be secured over and to seal the bottle mouth.

The pressure in the ring 66 is then allowed to escape and the table 6 lowered and the bottle removed from the head.

The number of reservoirs 3 need not necessarily be limited to one, as two or more each connected with the bottling head, and provided with separate cocks for controlling the passage of their contents to the head can be used, and if desired one of said reservoirs can be used for gas alone. Also it is immaterial whether the vacuum connection to the head, act through the ring 63 or through the top of the head, as before mentioned, while the latter is also provided with a vacuum gauge 87.

Alternative means for retaining the crown corks in their raised positions within the head 4, can consist of pins 88 caused to project horizontally, slightly into the head, under the action of spring (Figure 5).

When dealing with bottles adapted to be closed by a disc, such as is fitted to milk bottles, the bottling head (Figures 10, 11 and 12) comprises, a hollow casting 89 adapted to be secured to a casing 90 supported by a bracket from the hollow column 2, a piston rod 91 passing through the casing 90, while the piston 92 on said rod 91 is operable within the casting 89.

The head is provided around its lower edge or mouth with a rubber mouthpiece 93 shaped to receive the bottle mouth and held in position on said head by a retaining ring 94 made to screw on to the head. If desired the retaining ring 94 can be provided with a handle 94a or with flats to enable it to be screwed up to compress the rubber mouthpiece to the required degree.

A liquid inlet 96 opens into the head, a short distance above the rubber mouth piece 93, and is provided with a nipple 97 adapted to be connected with a reservoir, containing the liquid to be bottled.

Internally the head, is at a distance above the inlet 96 reduced in diameter to provide a circular stop 98 while a short distance below said stop small pins 95 are caused to normally project slightly into the head under the action of springs.

The diameter of the piston 92 is such that it is a neat working fit in the upper or reduced internal diameter of the casting 89, while the bucket leather or rubber 92a of the piston projects slightly below the body thereof, and an annular space 99 is left between the leather or rubber 92a of the piston and the body thereof.

The piston rod 91 does not fit its casing 90 which is made air tight at the top by a suitable gland and packing 90a. Also the rod 91, contains a vertical port 100 which communicates at its lower end with the space in the head below the piston 92 and at its top

end said port 100 connects with a radial port 101 (Figure 11) opening into the casing 90.

The interior of the piston rod casing 90 communicates with the air exhauster or ejector 7 preferably by a connection from a nipple 102 to the pipe 49 so that vacuum created can act in the casing 90 and also through the port 100 in the rod 91 and in the space in the head below the piston 92.

The piston rod 91 is in two portions, the upper portion screwing into the lower portion and passing through the gland at the top of the casing 90 and being connected to a hand lever 103 mounted similarly to the hand lever 85, and by means of which the piston 92, can be raised and lowered in the head.

Vertical recesses 104 (Figures 10 and 12) provided in the internal surface of the casting 89, open at their lower ends into the interior space of the head below the circular stop 98 and at their upper ends into said interior space above the piston 92, when the latter is raised.

It is desirable when bottling liquids such as milk which are easily contaminated or are susceptible to prevailing odours, to prevent the interior of the bottles, after the latter have been washed, from being subjected to such odours, and also to keep the milk from contacting with the latter. Therefore immediately the bottles have been washed, and before being exposed to the air, they are sealed or closed by means of the closures which will be ultimately permanently secured therein.

The closed bottles after sterilization (if necessary or desirable) are then passed to the bottling apparatus, the operation of which when adapted for bottling milk under vacuum is as follows.

The bottle with the usual paper or cardboard disc 105 inserted in its mouth, is placed on the table 6, and the latter allowed to rise under the action of the spring 10 in the column 2, until the disc 105 contacts with the leather or rubber 92a of the piston 92.

The latter is then moved upwards by means of the hand lever 103 the bottle following under the action of the spring 10.

At the commencement of the upward movement of the piston 92 a lower radial port 106 (Figure 10) in the rod 91, which was open to the interior of the head and consequently also to the air therein, owing to the piston 92 not fitting the lower portion of the head, is moved upwards so as to be closed to the interior of the head, whereupon the main port 100 in the rod 91 in communication with the piston rod casing 90, through the port 101, is placed under vacuum, acting through the casing 90 and nipple 102 connected with the pipe 49 from the ejector 7 and said vacuum acts on the paper or cardboard disc 105 in the bottle mouth.

Continued upward movement of the pis-

- ton 92 and bottle, results in the mouth of the latter contacting with the rubber mouth-piece 93 and under the pressure of the spring 10 makes an air tight joint therewith, the piston 92 being moved further upwards and taking the disc 105 with it, until the latter strikes the circular stop 98 and is detached from the piston 92. As soon as the piston 92 and disc 105 have passed the spring pressed pins 95 in the head, said pins 95 which have been pressed inwards by the piston and disc, project into the head again, and prevent the disc 105 from descending until such time as it is forced downwards by the piston 92.
- 15 Vacuum acting through the main port 100 in the piston rod 91 and the recesses 104, exhausts the air from the bottle and when the desired degree of vacuum is obtained therein liquid is permitted to pass to the head and from the latter into the bottle. After the liquid has reached the desired level in the bottle the supply thereof is cut off and if desired the air can be exhausted from the liquid contained in the bottle by allowing the vacuum to continue acting therein. Following this the piston 92 is moved downwards by the hand lever 103 to first force the disc 105 firmly into the mouth of the bottle to seal same, and secondly to eject the bottle mouth from the head, the vacuum acting on the disc 105 through the port 100 being destroyed by the air, allowed to enter the head on the unsealing thereof by downward movement of the bottle mouth, passing via the now opened lower radial, port 106, in the rod 91 to the main port 100 in the latter, whereupon the bottle which has been evacuated of air, filled and sealed under vacuum, can be removed from the apparatus.
- 20 A suitable form of air exhauster for use with the apparatus before described, comprises the ejector 7, having a casing 107 (Figure 13) adapted to be put in communication through the pipe 49 with whichever bottling head is being used, and containing an upper member 108 formed with a downwardly tapered passage opening into a passage which increases in diameter downwards, while below said upper member is a lower member 109 formed with a downwardly tapered passage opening into a passage which increases in diameter downwards, the lower member 109 screwing into the lower portion of the casing 107, and the upper member 108 being provided with a flange 108a which rests in a recess around the upper end of the casing 107. Communication between the pipe 49 and the passage way, formed through the upper and lower members 108, 109 is provided between the bottom of the upper member 108 and the top of the lower member 109 the former being entered slightly in the latter.
- 25 The water control valve 37 in the water supply pipe 110 to the ejector comprises a casing containing a downwardly tapered pas-

sage opening into a passage which increases in diameter downwards, a gate 111 operable by a sliding stem 112 passing through a stuffing box 113 and into the forked extension 41a (Figure 8) said gate 111 being slidable in said valve casing at the junction of the downwardly tapered and downwardly increasing passages therein for the purpose of controlling the passage of water through the passage way provided by the passages in the upper and lower members 108, 109 and the passages in the valve casing.

30 A water outlet pipe 113 is connected to the lower or discharge end of the ejector casing.

What I do claim and desire to obtain by Letters Patent of the United States of America is:—

35 1. Apparatus for bottling liquids, comprising a bottling head in communication with a source of vacuum and constructed to be placed in communication with a reservoir for the liquid to be bottled, means for pressing a bottle mouth and a closure therefor into said head, means in said head for applying the closure to the bottle mouth to seal the same, a metal ring through which air is exhausted from said head and the bottle and through which the latter is filled, a retaining ring secured to said head, an expanding ring for sealing the entrance to said head around said bottle located between said metal ring and said retaining ring a chute for delivering bottle closures to said head, a piston operating in said head, a sleeve in said head for receiving the rod of said piston, said rod being fitted with pins entering slots in the sleeve, a vertical rod working in said sleeve, a hand lever mounted on a fixed support above the bottling head connected to said rod and a connection between said rod and said piston rod.

40 2. Apparatus for bottling liquids comprising a bottling head, means for placing the interior of said bottling head under vacuum, means for passing a liquid through said head into a bottle placed therein, means sealing said head and bottle opening from the atmosphere, a piston operable in said head to affix a closure to said bottle while said sealing means is operative, a piston rod for said piston having a vacuum passage therein, and spring-actuated projections provided in the head for retaining a bottle closure in raised position during the period of evacuation of air from said bottle and the filling of the bottle with liquid.

45 In testimony whereof I have signed my name to this specification.

50 ERNEST BLAKELOCK THUBRON.
